UNITED STATES PATENT OFFICE.

ROLLIN L. DRAKE, OF PORT ARTHUR, TEXAS, ASSIGNOR TO THE TEXAS COMPANY, OF NEW YORK, N. Y., A CORPORATION OF TEXAS.

CLOSURE FOR CONTAINERS.

Application filed September 23, 1922. Serial No. 589,973.

To all whom it may concern:

Be it known that I, ROLLIN L. DRAKE, a citizen of the United States, residing in Port Arthur, county of Jefferson, and State of Texas, have invented certain new and useful Improvements in Closures for Containers, of which the following is a specification.

This invention relates to closure means for containers and has special reference to sealing and closure means for metallic receptacles.

This invention contemplates the provision of a cap, lid, top, or other closure that is adapted to be spun or rolled into position in such a manner as to form a tight seal and provided with a screw neck or thimble adapted to serve as an outlet for a container.

Various features and advantages of the invention will be set forth hereinafter and I will now describe the same with reference to the drawings and point out the novel features thereof in the appended claims.

In the drawings which show in detail caps and closures constituting examples of the invention and also indicate the process of making same:

Figure 1 is a sectional elevation of a device constituting an example of the invention and showing the parts assembled ready for the crimping operation.

Figure 2 is a sectional elevation of the device of Figure 1 at the completion of the crimping operation.

Figure 3 is a modified form of the invention.

In the example of the invention shown in Figures 1 and 2 10 represents a portion of a can or container equipped with a filling or dispensing opening about which is formed a peripheral flange 11 which is preferably constructed with a curved portion 12. A substantially concave or dished cap member 13 is provided to form a closure in or over the opening and is preferably of sufficient concavity as to extend to the base of the flange or somewhat below the base as illustrated. The cap is preferably constructed with the edge 14 bent or turned, as shown in Figure 1, so that it may readily be assembled in position on the flange ready for the capping or crimping operation. A neck or screw thimble 15 is inserted within the cap member 13.

With the parts thus assembled a capping

tool is employed to suitably crimp the members into position. In performing this operation one or more external rollers are employed which exert pressure inwardly toward the center of the cap so that the portion 14 of the cap is spun against the flange in the position indicated in Figure 2 and at the same time inner rollers arranged to exert pressure outwardly operate to draw the metal and bulge or expand a portion of the neck 15 and cap 13 in such manner that the neck is expanded against the cap thus fixing it in permanent position and simultaneously a seal is formed by the bulging or expanding of the cap 13 underneath the flange 11 and against the curved portion 12 so as to form the curved joint of the nature of that shown in the drawing.

The neck 15 may be secured in various ways besides being rolled in and expanded within the cap 13. For example, the neck 15 may be provided with an externally threaded portion adapted to cooperate with an interiorly threaded portion of the cap 13, or the neck or the cap, the one or the other, may be equipped with lugs adapted to engage in a groove in the other, or the parts may be attached by soldering.

The screw thimble 15 is provided with a cap 16 which is preferably knurled as at 17. In using this form of cap the bottom of the member 13 may be cut out by the customer or consumer and the cap 16 serves as a removable closure to protect the contents of the container.

In Figure 3 is shown a container of substantially cylindrical form and having a lid or end 18. The can or container 22 is equipped near the end thereof with a shoulder preferably in the form of a curved portion 19 and the lid 18, which is of substantially concave or dished formation, is adapted to be drawn and bulged or expanded against this curved portion to form the curved joint shown and the outer edge 14 of the lid is turned over the end of the can so as to form a tight closure.

The can or container 22 is provided with a screw neck or thimble 20 fitted into the cap member 18 and bulged or expanded therein as shown. A threaded cap or lid 21 provides a movable closure for the container.

It has been found that the sanitary seal described herein effects a very efficient clo-

sure, the double joint, including the curved joint, forming a substantially fluid tight seal. If desired, however, a suitable sealing composition may be employed to add to the efficiency of the seal. Thus sealing material may be inserted underneath the curved portion 14 or shoulder 19, for example, prior to the crimping operation. In the case of containers intended for volatile or inflammable fluids, such as petroleum oils, particularly the lighter products thereof, it is generally desirable to use a sealing material. Where the cap, lid, or seal is put in place after the container is filled with fluid it is best to employ a sealing material that is insoluble in the fluid and which will dry rapidly.

It is evident that various modifications of my invention may be made within the spirit and scope thereof and I desire that only such limitations be imposed as are indicated in the appended claims.

What I claim is:

1. A container having adjacent an end thereof a curved portion, a closure for said container comprising a substantially concave member the edge of which is spun over said end and a portion of which is rolled against said curved portion so as to make a curved joint therewith, a threaded thimble rolled into said concave member and a cap therefor.

2. In combination with a container having an opening therein and formed with a peripheral flange provided with a curved portion, a substantially concave cap spun over said flange and expanded against said curved portion so as to form a closure in said opening and a threaded thimble rolled into said cap.

3. In combination with a container having an opening therein and formed with a peripheral flange, a substantially concave cap rolled over said flange so as to form a closure in said opening, and a substantially cylindrical member rolled into said cap.

4. In combination with a container having an opening therein and formed with a peripheral flange, a substantially concave cap crimped over said flange so as to form a closure in said opening, a hollow cylindrical member rolled into said cap, and a movable closure member for said cylindrical member.

5. In combination with a container having an opening therein and formed with a peripheral flange, a substantially concave cap rolled over said flange so as to form a closure in said opening, a threaded thimble expanded within the concave cap, and a detachable closure member on said thimble.

In witness whereof I have hereunto set my hand this 1st day of September, 1922.

ROLLIN L. DRAKE.
